CLAIM

The ornamental design for a "computer copy holder with a floral pot motif", as shown and described.

DESCRIPTION

FIG. 1 is a front elevational view of a computer copy holder with a floral pot motif showing my new design; FIG. 2 is a left side elevational view of the copy holder; FIG. 3 is a right side elevational view of the copy holder; FIG. 4 is a rear elevational view of the copy holder; FIG. 5 is a top plan view of the copy holder; and, FIG. 6 is a bottom view of the copy holder.

The fragmentary portion of a computer monitor depicted by means of broken lines in FIG. 1 has been shown for illustrative purposes only and forms no part of the claimed design.

The attachment portion has been shown broken away in FIGS. 4, 5, and 6 for convenience of illustration.
